UNITED STATES PATENT OFFICE.

OTTO KUEPPERS, OF PHILADELPHIA, PENNSYLVANIA.

IMPROVEMENT IN NECK-TIES.

Specification forming part of Letters Patent No. 148,221, dated March 3, 1874; application filed January 9, 1874.

To all whom it may concern:

Be it known that I, OTTO KUEPPERS, of the city and county of Philadelphia and State of Pennsylvania, have invented a new and useful Improvement in Neck-Ties; and I do hereby declare the following to be a full, clear, and exact description thereof, which will enable those skilled in the art to make and use the same, reference being had to the accompanying drawing forming part of this specification, in which drawing—

Figure 1 represents a rear view of a scarf constructed according to my invention. Fig. 2 is a similar view of a bow made according to my invention.

The remaining figures are details, which will be referred to as the description progresses.

Similar letters indicate corresponding parts.

This invention consists in a neck-tie, the several folds, seams, or parts of which are connected together by metallic clasps, in such a manner that said parts become firmly connected, and that the cost of making such neck-ties, scarfs, or bows is materially reduced.

In the drawing, the letter A designates a neck-tie, the various folds, seams, and parts of which are connected together by metallic clasps a, one of which is shown in an enlarged scale in Fig. 3. In preparing my neck-tie, I take the lining d, Fig. 4, and pass through it the points of two or more clasps at the proper places, according to the form of the article to be produced. Then I fold the silk, satin, or other material from which the neck-tie is to be made, over the same, and, after passing the points of the clasps through this material, I clinch said points, and thereby the lining and the covering material become firmly united.

Said clasps may also be used to hold the overlapping edges of the covering material in position, as shown in Fig. 6; or said overlapping edges may be fastened together by sepa-

rate clasps, as shown in Fig. 5. These retaining-clasps may be concealed in the inside of the covering material, as shown in Fig. 7.

For cheap articles, where the covering material does not inclose the lining completely, the covering material and the lining are fastened together by clasps, as shown in Fig. 8.

When a shield, B, is to be used in the neck-tie, the neck-tie proper, after being completed in the manner above described, is secured to said shields by means of clasps, in the manner shown in Fig. 2, and by this method of fastening a firm, durable, and cheap connection is effected.

When the shield is to be partially or wholly covered with silk, satin, or other suitable material, I fasten the covering material by means of clasps, as shown in Figs. 9 and 10, where Fig. 9 shows a shield completely covered, and Fig. 10 a shield partially covered.

By means of these clasps I am enabled to manufacture neck-ties at a comparatively small cost, since the labor of inserting and clinching the clasps can be performed by boys or girls having but little practice, while in the ordinary method of manufacturing neck-ties practiced hands are required for the purpose of sewing the parts and seams together. And, beside this, by my method of fastening the parts with clasps the neck-ties become more durable than they are when sewed according to the present method of manufacture.

What I claim as new, and desire to secure by Letters Patent, is—

As a new article of manufacture, a neck-tie, the seams of which are united together by the metal clasps a in the manner herein shown and described, for the purpose specified.

OTTO KUEPPERS.
